UNITED STATES PATENT OFFICE.

TOM B. MYERS, OF MARSHALL, TEXAS.

TORPEDO.

Application filed April 16, 1921. Serial No. 462,055.

This invention relates to improvements in torpedoes and more particularly to the pistol mechanism employed in the combustion flask for igniting the fuel used in superheating the motive fluid.

As is well-known to those skilled in the art, torpedoes now in general use are driven primarily by compressed air after it has passed through the combustion flask where 10 it is superheated in the presence of steam by means of an alcohol burner or the like, the entire products of combustion so called passing directly from the combustion flask to the turbines.

15 It sometimes happens that the fuel is not ignited resulting in what is known as a cold shot and it is one of the objects of the present invention to provide a reliable and efficient pistol for igniting the fuse which in 20 turn ignites the alcohol burner thereby insuring a hot shot.

A further object is to provide a simple and practical mechanism of the above general character which will be operated by the 25 pressure of the fuel as it is admitted to the combustion flask thereby properly timing the firing of the fuel cartridge with respect to the admission of fuel to the flask.

With these and other objects in mind 30 which will appear obvious from the following disclosure, attention is directed to the accompanying sheets of drawings illustrating one of various possible features of the invention and in the several figures of which 35 corresponding parts are denoted by similar reference characters.

Figure 1 is an elevational view, partly in section showing the pistol in cocked or armed position.

40 Figure 2 is a similar view showing the parts at the moment of firing, and,

Figure 3 is a sectional view showing the parts in position immediately after firing.

Referring to these drawings in detail, 5 45 denotes a casing adapted to be screwed into the head of the combustion flask by means of the threaded connection 6. This casing is provided with a cap 7 threadedly connected therewith and containing the fuse 50 holder 8 carrying the fuse or cartridge 10. The upper part of the casing forms a chamber 11 opened through the port 12 to the pressure of the fuel. This chamber must 55 fill first and therefore gives the desired delay after fuel pressure arrives. Within the cap is a tubular member 13 carrying an

arming plunger or piston 15 provided with a stem 16 sliding within a tubular member 17 mounted within the firing plunger 18. The piston is loosely fitting within the tubular member 13 thereby permitting the air to leak past to the flask until the parts assume the position shown in Figure 3. This plunger is provided at its lower end with a firing pin 20 adapted to engage the cap of the fuse 10. Acting between a fixed support or sleeve 21 and the upper inner surface of the plunger 15 is a return spring 22 and between the firing plunger 18 and the same surface of the plunger 15 is a firing spring 23. The firing plunger 18 it will be noted by reference to Figure 1 is provided with a plurality of recesses 24 in which are a plurality of balls 25 engaging recesses 26 in the supporting member 21. These balls are held in place by the end 27 of the tubular member 17. As long as the parts remain in normal position shown in Figure 1, that is, unaffected by any fuel pressure the pistol remains in locked armed position but when 80 the fuel is admitted through the port 12 pressure builds up within the cap 7 and acts on the head of the arming plunger 15 forcing the same downwardly to the position shown in Figure 2 when the boss 28 85 engages the upper end of the tubular member 17. As the pressure increases, the piston or plunger 15 forces the tubular member 17 downwardly until the recessed portion 30 comes opposite the balls 25 whereupon they 90 are permitted to drop out of the recesses 26 and permit the firing plunger 18 to move suddenly downwardly under action of the firing spring 23, the firing pin 20 thereupon engaging the cap in the fuse 10 and igniting the same which continues to burn for a sufficient length of time to insure the ignition of the fuel previously admitted to the combustion flask.

It is believed that the above clearly describes the construction, operation and method of use and a further statement is unnecessary. The invention is of simple and practical construction, reliable and efficient in use and operation and is so timed with 100 respect to the admission of fuel to the combustion flask as to insure the obtaining of a hot shot when the torpedo is fired.

Without further analysis, the foregoing will so fully reveal the gist of this invention 110 that others can by applying current knowledge readily adapt it for various applications

without omitting certain features that, from the standpoint of the prior art, fairly constitute essential characteristics of the generic or specific aspects of this invention, and, therefore, such adaptations should and are intended to be comprehended within the meaning and range of equivalency of the following claim.

What I claim is:—

10. In a device of the character described, in combination, a casing carrying a firing mechanism adapted to be mounted on the combustion flask of a torpedo, said casing having an inlet port adapted to be connected with a suitable source of fluid under pressure, a firing pin movably mounted in said casing, a sleeve mounted in the casing, a

fuse adapted to be engaged by the firing pin, a plunger subjected to said fluid pressure through said inlet port, locking means for the firing pin adapted to be released after predetermined movement of the plunger, said locking means comprising a plurality of balls engaging in recesses in the firing pin and sleeve, and spring means between the plunger and firing pin normally uncompressed but compressible on movement of the plunger, said spring means forcing said firing pin against said fuse after the locking means has been released. 20 25 30

Signed at Marshall, Texas, this 23rd day of March, 1921.

TOM B. MYERS.
